F. W. Becken
ATTORNEY

UNITED STATES PATENT OFFICE.

JOSEPH W. PUTNAM, OF EAST ORANGE, NEW JERSEY.

BOILER MOUNTING.

Application filed October 21, 1922. Serial No. 596,005.

To all whom it may concern:

Be it known that I, JOSEPH W. PUTNAM, a citizen of the United States, and a resident of East Orange, in the county of Essex and 5 State of New Jersey, have invented certain new and useful Improvements in Boiler Mountings, of which the following is a specification.

This invention relates to a baffle wall or 10 the like for boiler tubes and to the method of making the same.

In the art of boiler mounting, as heretofore practiced, it has been the custom either to imbed the boiler tubes in a solid wall 15 formed from plastic refractory material, or else to build channels, by means of pre-formed bricks, extending diagonally with respect to the boiler tubes and to fill said channels with plastic refractory material. 20 In the former instance it is impossible to replace a boiler tube without dismantling the wall or a large part thereof, in addition to which the expansion due to heat tends to produce cracks in and distortions of the 25 wall; and in the latter instance, although the replacement of a tube is possible, the construction is expensive and it is difficult to obtain the cementitious bond rendered necessary by this construction between an 30 old wall section and a new wall section. In addition to this it is not practical to make the bricks less than one inch thick because such bricks cannot be molded without warping, and it is therefore not possible to use 35 the preformed bricks when the channels are small. A like difficulty is also encountered when replacement work is carried on in old boilers where the tubes are badly warped. A further advantage accruing from dis- 40 pensing with preformed bricks in building channels is that it is not necessary to carry a stock of preformed bricks of different sizes, which results in a reduction of the cost of construction. It has also been at- 45 tempted to build a wall entirely of pre-formed bricks, but this is unsatisfactory because, when replacing the bricks, smaller bricks than those originally employed have to be used in order to get them into position.

50 I have found that these disadvantages may be overcome by building a wall devoid of pre-formed bricks by successively molding, in position with respect to the boiler tubes, a plurality of independently removable wall sections of refractory material and in interlocking with each other said molded

wall sections during and by the process of molding the same.

In the accompanying drawings the invention is disclosed in a concrete and preferred 60 form in which:

Fig. 1 is a vertical sectional face view on the plane of line 1—1 of Fig. 2 showing a wall embodying the invention.

Fig. 2 is a vertical sectional view on the 65 plane of line 2—2 of Fig. 1.

Fig. 3 is a perspective view of one of the molding elements of sheet material.

The boiler tubes are indicated at 1 and are usually arranged in staggered relation in 70 cross section as shown. 2 indicates a plurality of wall sections molded in position with respect to the boiler tubes. These wall sections are independently removable and the adjacent edges of said section are shaped 75 so as to interlock with each other. This shaping is produced by interposing, during the molding operation, mold members 3 of sheet material suitably shaped as by means of corrugations or otherwise. Mold members 3 may be of any suitable sheet material 80 such as metal, paper or cardboard and are of very slight thickness. It will be understood that in building the baffle wall, supported by bridgewall 4 or otherwise, the operator 85 will start say at the lower left hand corner of Fig. 1 and will first mold the mold section 2^a, the refractory material being placed between the bridgewall 4 and mold member 3^a. That surface 2^b which is adjacent to 90 mold member 3^a receives the shape of said mold member. The next wall section 2^c is now molded on top of mold member 3^a and is bounded by mold member 3^b.

It will now be understood that a plurality 95 of wall sections are built up having shaped surfaces that are formed during and by the molding operation, and that the sheet material of mold members 3 is so thin and the corrugations thereof so deep that interlocking 100 of the wall sections takes place. The mold members are left in position and may or may not be destroyed by the heat when the boiler is fired. The heat of the boiler is, however, so intense that expansion of the 105 tubes and wall sections takes place and produces a gas tight partition and this although there is no bond between adjacent wall sections. Mold members 3 may run in any direction, such as vertically or horizontally, 110 or diagonally in the same or different directions or a combination of these may be used.

When a bent tube is to be replaced, that wall section in which the tube is imbedded is removed, the operation being easy because of the shrinkage which takes place between the wall sections when the boiler cools off and because there is usually no cementitious bond between adjacent sections. It is also easy to replace a wall section because interlocking corrugations and not a new cementitious bond are depended upon to support the structure. If desired, the replaced wall section may be filled in directly on the shaped faces of the adjacent wall sections, but preferably new molding members are inserted between the old wall sections and the new sections.

I claim:

1. The process of building a baffle wall, devoid of pre-formed bricks, for boiler tubes which consists in successively molding, in position with respect to the boiler tubes, independently removable wall sections of refractory material having opposing faces with mutually interlocking indentations and projections, and in interlocking with each other said molded wall sections during and by the process of molding the same.

2. The process of building a baffle wall, devoid of pre-formed bricks, for boiler tubes which consists in successively molding, in position with respect to the boiler tubes,

independently removable wall sections of refractory material, and in interposing during the molding operation, between adjacent wall sections, molding members of sheet material shaped to produce complementary shaped surfaces on adjacent wall sections that interlock during and by the process of molding.

3. A baffle wall or the like devoid of pre-formed bricks, for boiler tubes comprising: a plurality of independently molded wall sections of refractory material, each mold section having a shaped surface that interlocks with a complementary shaped surface of an adjacent molded wall section.

4. A baffle wall or the like, devoid of pre-formed bricks for boiler tubes comprising: a plurality of independently molded wall sections of refractory material; each mold section having a shaped surface that interlocks with a complementary shaped surface of an adjacent molded wall section, and molding members of sheet material, shaped to produce the said complementary shaped surfaces on adjacent wall sections, interposed between adjacent wall sections.

Signed at New York City, in the county of New York and State of New York, this 19th day of October, 1922.

JOSEPH W. PUTNAM.
